UNITED STATES PATENT OFFICE

BENJAMIN J. TRILLER, OF DUBUQUE, IOWA

IRONING AND WALL TABLE

Application filed May 19, 1927. Serial No. 192,560.

This invention relates to improvements in combined cabinet ironing boards and tables, and particularly to a table designed to co-operate with a cabinet of an ironing board.

Recently, cabinet ironing boards have been placed on the market in which the ironing board per se is housed within a door or within a wall cabinet, and in each case, the door or cabinet has hinged panel members arranged when in one position, to form a support for the ironing board, while the latter is in service position.

The primary object of the present invention is to provide a table top which may be interlocked with the door or cabinet or one of said panel members, or which may be interlocked with both the door or cabinet, and one of said panel members, and form an auxiliary table for use in a kitchen or the like.

A further object of the invention is to provide a table top for this purpose, formed of folding leaves, which, when folded, may be stored in a relatively small space.

Another object is to furnish novel means for interlocking the table top to the door or cabinet.

With the foregoing objects outlined and with other objects in view which will appear as the description proceeds, the invention consists in the novel features herein-after set forth in detail, illustrated in the accompanying drawing, and more particularly pointed out in the appended claims.

Referring to the drawing,

Fig. 1 is a front view of a wall cabinet ironing board, partly broken away, and illustrating the type of cabinet ironing board with which the improved table top may be combined.

Fig. 2 is a vertical sectional view of the same with the door panels in position to support the ironing board or table top, and with parts of the ironing board broken away to facilitate illustration.

Fig. 3 is a top plan view of the table top, and illustrating the manner in which it is attached to the cabinet.

Fig. 4 is a vertical sectional view of a detail taken on line 4-4 of Fig. 3.

Fig. 5 is an elevation of a portion of the cabinet and illustrating a modified form of locking device for securing the panel sections in closed position.

In the drawing, 1 and 2 designates the side bars, and 3 and 4 the top and bottom cross rails, respectively of a cabinet which is adapted to be secured on the face of a wall 5, or imbedded in the latter. The space between the parts 1, 2, 3 and 4 forms a compartment to receive an ironing board 6, while the latter is stored.

Each of said bars is provided with a vertical groove 7, forming guides for a follower 8. The latter slides vertically in the guides and is preferably formed of heavy wire. The upper end of the follower is pivotally connected at 9 to the lower end of the ironing board, and the sides of the follower have shoulders 10 to engage stops 11 which block the grooves 7 at one point. Each of these stops is provided with a notched metal protector 12, cut from its opposite ends to form tongues 13 which are bent into the grooves and engage the upper 70 and lower surfaces of the stop 11.

The bridge bar 14 spans the upper portion of the space between the side bars 1 and 2, and has its ends counter-sunk in and secured to the side bars by any suitable means, such as screws 15. This bridge bar functions as an abutment for the upper end of the ironing board, when the latter is stored, and it protects the wall or rear surface of the ironing board compartment against impacts imparted by the ironing board while the latter is being placed in vertical position.

The ironing board compartment is closed by a door 17 made up of an upper panel 18 and a lower panel 19. The lower panel is pivotally connected to the bottom rail 4 by means of hinges 20 which permits that panel to swing outwardly into the position shown in Fig. 2.

Hinges 21 are arranged on the inner sides of the panel members and pivotally connect the same, as shown in Fig. 2, so that the upper panel 18 may be swung into a horizontal position.

The upper panel is provided at its upper end with a pair of metal guide members 22, secured to the panel by screws 23 or the like, and provided with oppositely extending fingers 24 which slide in the guides 7. When the members 22 are in their uppermost position, they occupy recesses 25, cut in the top rail 3, and when they are in their lowest position, the pins 24 occupy the upper notches of the protectors 12 of the stops 11.

Spring clips 16, of any suitable construction, are secured to the rear side of the upper panel, and they engage pins 16a on the side bars 1 and 2 for detachably securing the panels in closed position.

The upper panel is provided at its lower end with an operating knob 26, and for the purpose of describing the operation, we will now assume that the parts are in the position shown in Fig. 1. With the elements thus positioned, the operator grasps the knob 26 and pulls the same outwardly. This causes the pins 24 to slide downwardly in the grooves 7 until they engage the stops 11, and at such time, the panel members 18 and 19 will be in the position shown in Fig. 2, and it may then act as a support either for the ironing board 6, or for the table top 27 which will be described in detail hereinafter. Assuming now that the table top does not rest upon the panel 18, and that it is desired to use the ironing board; the operator grasps the upper end of the board 35 and pulls the same slightly forward. The board is then raised upwardly until the shoulders 10 of its follower engages the stops 11. Then the board is swung in a clockwise direction to bring the same into a horizontal position on the panel 18. In this position, the knob 26 occupies a recess 28 in the under side of the board, and this interlocking means prevents the board from moving laterally while it is in service position.

Cabinet ironing boards of the type just described, are now well known, and in the present invention, the details thereof have been improved, and in addition, the table top 27 is combined therewith in a novel manner.

This table top may be formed in any desired way, falling within the spirit of the invention, but it is preferred to make the same of a pair of leaves 29 and 30 hinged together at 31 by counter-sunk hinges, the upper surfaces of which lie flush with the upper surface of the leaves when the latter are unfolded. The top 27 has a reduced extension 32 arranged at one end, and of a width substantially equal to the width of the interior of the ironing board compartment, so that when this extension is inserted between the side bars 1 and 2, and against the ironing board, the top will be prevented

from moving laterally. The top may be interlocked with the cabinet in any suitable manner, but it is preferred to use the following instrumentalities. The side bars are provided with screw eyes 33 to receive hooks 34 which are pivotally mounted at 35 in recesses 36 in the top 27. These elements detachably connect the top to the side bars 1 and 2, and in order to secure the top to the panel 18, each leaf is provided at its inner edge with a recess 36, as shown in Fig. 4, to receive the head 37 of the knob 26. These recesses have threads 38 on their under sides to engage the bottom of the head 37, and to thus prevent the table top from being pulled away from the panel 18, as long as the leaves 29 and 30 are in the full open position. The leaves have shallower recesses 39 to receive the stem 40 of the knob.

It is obvious that the cabinet may be made sufficiently roomy to house the top 27, or the top may be stored in any other suitable place, and while the top is in service position, as shown in Figs. 2 and 3, it may be used as a kitchen table or as a dining table.

In the modification shown in Fig. 5, the spring clips 16 and the pins 16a with which they cooperate, are to be eliminated, and the knob 26 is modified so that it will effect the locking and unlocking of the panels. To this end, a knob 26a is swivelled in the upper panel 18a, and its stem is provided with oppositely extending arms 26b. Each of these arms is pivotally connected to a sliding bolt 26c, the end of which is adapted to enter a hole 26d in the side bars of the cabinet.

Obviously, when the knob is turned in a counter clock-wise direction, the bolts 26c will be withdrawn from the holes 26d, and the panels may then be pulled forwardly.

From the foregoing it is believed that the construction, operations and advantages of the invention may be readily understood, and it is apparent that changes may be made in the details disclosed without departing from the spirit of the invention as expressed in the claims.

What is claimed and desired to be secured by Letters Patent is:

1. In a structure of the character described, a cabinet having vertical guides, a closure for the cabinet provided with guide elements working in said guides, stops associated with said guides, and metal protectors for the stops, including substantially H-shaped plates having tongues arranged at angles thereto, and engaging said stops, certain of said tongues forming abutments for the guide elements of said closure.
2. In a structure of the character described, a stop, and a metal protector for the stop, said protector consisting of a sheet metal plate having rearwardly extending

tongues, and notches positioned adjacent to said tongues.

3. In a structure of the character described, a flat support having an element projecting above the same, a top resting on the upper surface of said support, and formed of leaves, hinges separate from the support and hingedly connecting said leaves, the adjacent edges of said leaves being provided with means to automatically interlock with said projecting element when the leaves are fully opened on the support.

4. In a structure of the character described, a cabinet having a closure formed of hinged sections adapted to be moved into a position to form a support, a table top resting on one of said sections, and manually operated means arranged forwardly of said cabinet for connecting the top to said cabinet.

5. In a structure of the character described, a support member, and a table top member, one of said members being provided with a knob, and the other formed of hinged leaves having recesses to receive and interlock with said knob.

6. A table top for use with cabinet ironing boards and the like, comprising a pair of leaves hinged together and each provided with a reduced extension adapted to extend into an ironing board cabinet or the like, the meeting edges of the leaves being recessed on their under sides to interlock with a knob or the like when the leaves are unfolded.

7. In a structure of the character described, a cabinet including a body and a door formed of upper and lower sections, means hingedly connecting the lower edge of the lower section to the body, means hingedly connecting the sections together, means slidably connecting the upper edge of the upper section to the body, said sections being adapted to be moved into a position in which the upper section lies in a horizontal position to form a support, a table top resting on the upper section and having an extension projecting into the body, means for detachably interlocking the top to the body, and means for detachably interlocking the top to said upper section.

In testimony whereof I affix my signature.
BENJAMIN J. TRILLER.
